UNITED STATES PATENT OFFICE

WALTER E. TAYLOR AND JOSEPH M. TAYLOR, OF RICHMOND, KENTUCKY

PLANT BED BURNER

Application filed May 21, 1930. Serial No. 454,344.

This invention relates to a plant bed burner and it has more particular reference to a structure which is especially designed to burn tobacco beds.

It is a matter of common knowledge that tobacco beds are burned to expedite and facilitate the growing of tobacco. As a general rule, this particular phase of tobacco growing involves a hardship and task for the attendant. The work is tedious and slow and at the present time make-shift means and methods are resorted to.

This necessitates the building of fires and raking of the fire by hand. Due to excessive heat, it is difficult for the attendant and farm hands to face the hot fire and as a general rule, it is necessary to row and spread the fire by pushing and pulling it with forks and other make-shift hand implements.

With the foregoing difficulties in mind, we have evolved and produced a simple and economical portable device on which the fire may be built in a substantially intact manner, the device being in the nature of a sled equipped with an appropriate open-work grid or grate.

This portable grate-equipped sled economizes on fuel, saves time and labor, and permits the complete fire on the grate to be drawn from one area to another to facilitate burning of the bed.

The particular details embodied in this structure will become more readily apparent from the following description and drawings.

In the drawings:

Figure 1 is a top plan view of the complete device.

Figure 2 is a longitudinal sectional view of the same.

Figure 3 is a cross section taken approximately on the plane of the line 3—3 of Figure 1.

As before stated, the device is in the nature of a portable grate equipped sled. The sled is composed of a plurality of spaced parallel longitudinal runners 4 whose front ends are upturned as at 5 and whose rear ends 6 are upturned in a substantially similar manner. The rear ends are secured together by a tie bar 7. There is a similar tie bar 8 at the front.

The forward end of the outermost runners includes horizontal extensions 9 having terminal hooks 10 with which suitable draft means (not shown) may be connected for pulling the sled over the ground. Extending across the front and attached to the extensions 9 is a connecting bar 11. Attached to this bar are inclined braces 12 extending downwardly and fastened to a companion connecting strip or bar 13.

The numeral 14 designates generally the fire receiving grate. This is in the nature of woven wire fabric of appropriate proportions and texture. This is laid on the runners and secured thereto by a pair of converging fastening strips 15 which extend rearwardly and connect with a cross bar 16. Supplemental attaching strips are represented at 17 and these are suitably fastened to the runners therebeneath.

There is another clamping and attaching strip at 18 near the rear of the structure and the rear end of the grate indicated at 19 is extended upwardly to form an apron and this is anchored on the bar 7 at the rear of the runners.

The forward apron 20 is fastened to the bar 8. The gist of the structure, it will be seen is in the provision of appropriately bent runners for smooth draft and dragging purposes, together with an openwork grate mounted thereon and suitably fashioned to accommodate the wood and other fuel used in building the fire thereon. Particularly do we draw attention to the provision of the curved ends of the runners and especially to the forward portion of the structure which is provided with the outstanding extensions 9 and the draft connecting hooks 10.

Moreover, we wish to emphasize the rigid construction incorporating the multiplicity of inclined braces 12 as well as the parts 15, 16, 17 and 18 for securely fastening the grate in a taut state on top of the runners.

In practice, the attendant prepares the bed as is usual for burning. The device saves approximately one-half of the labor on preparing the wood. It is permissible with this device to burn rougher coarser, heavier and more wood such as would otherwise be waste.

when using the old and obsolete hand process. After a good fire is once started it is permissible to burn either seasoned or green wood with successful results.

5 The device consumes approximately half as much wood as would be utilized by the hand method. The device is built on the ground, thereby keeping the fire next to the ground where it is needed. The grate is of
10 steel woven wire appropriately reinforced for strength and the openwork design permits the hot coals to be dropped through on the ground and this makes an exceptionally good fertilizer for the plant. The sled-like device
15 can be hooked to any sort of draft appliance and moved from place to place so as to expedite ground coverage in the bed burning operation.

It is thought that persons skilled in the
20 art to which the invention relates will be able to obtain a clear understanding of the invention after considering the description in connection with the drawings. Therefore, a more lengthy description is regarded as un-
25 necessary.

We claim:

1. A plant bed burner of the class described comprising a sled including a plurality of spaced strips, each strip having each
30 end bent upwardly, said strips forming runners, cross strips resting on the upper faces of the runner strips and connected therewith, each of the cross strips being spaced inwardly from the turned up portion of each
35 runner strip, a cross strip connected to the turned up portions of the runners at each of the forward and rearward ends of the device, wire mesh resting on the runners and the cross strips and having its ends connect-
40 ed to the strips which are connected to the turned up portion of the runners whereby the ends of the wire mesh extend upwardly to form aprons.

2. A plant bed of the class described comprising a plurality of runner strips spaced apart and each having its ends turned upwardly, a cross strip at each end of the device and connected with the curved portion of the runner strips, a sheet of wire mesh resting on the runner strips and having its ends connected with the cross strips, a pair of cross strips placed inwardly from the turned up ends of the runners and extending across the wire mesh, the portions of the wire mesh be-
50 tween the pair of strips forming upwardly extending aprons, a cross strip connected with the upper ends of the front portions of the runner strips, and brace bars connecting the last mentioned strip with the forward
55 or front strip which passes across the wire mesh.

In testimony whereof we affix our signatures.
